UNITED STATES PATENT OFFICE.

CHARLES W. ECKER, OF CANTON, OHIO, ASSIGNOR TO THE BERGER MANUFACTURING COMPANY, OF CANTON, OHIO, A CORPORATION OF OHIO.

METAL WINDOW-SASH.

No. 823,266.

Specification of Letters Patent.

Patented June 12, 1906.

Application filed February 7, 1905. Serial No. 244,641.

To all whom it may concern:

Be it known that I, CHARLES W. ECKER, a citizen of the United States, residing at Canton, in the county of Stark and State of Ohio, have invented certain new and useful Improvements in Metal Window Sash and Frames; and I do hereby declare that the following is a full, clear, and exact description of the same, reference being had to the annexed drawings, making a part of this specification, and to the numerals of reference marked thereon, in which—

Figure 1 is a side elevation showing two window-sashes placed in proper position. Fig. 2 is an edge view of one of the window-sash bars or rails, showing the same located in the frame or guide. Fig. 3 is a view similar to Fig. 1, except it shows the opposite side of the window-sash proper. Fig. 4 is a view showing the portions of the sash and frame, also illustrating the pivotal connection of the sash and the manner of connecting the stiles together. Fig. 5 is a view showing a portion of the window frame or casing and illustrating one of the sash-bars tilted. Fig. 6 is a detached view of one of the miter ends of the sash. Fig. 7 is a view showing a portion of the opposite or connected sash rail or bar. Fig. 8 is a view of the sash-frame proper, showing the stile removed and a portion of the sash-bars broken away.

The present invention has relation to window sash and frame formed of metal and in connecting the metal portions of the sash-frame portions together, so as to constitute a rectangular structure especially to hold the pane of glass in proper relative position and to provide for the movement of the sash-frames.

Similar numerals of reference indicate corresponding parts in all the figures of the drawings.

In the accompanying drawings, 1 represents the horizontal rails or bars, and 2 the vertical rails or bars of the sash-frames proper, which are connected together at their ends, as hereinafter described. Each rail or bar of the window-sash proper is formed of a single piece of metal bent to form the entire portion of the sash rails or bars and are so formed that they will properly hold the panes of glass desired to be connected thereto. The rails or bars 1 and 2

may be formed so as to produce a channel 3, which channel is bounded by the portions 4, 5, said portions being folded against each other, as illustrated in Fig. 4.

The vertical rails 2 are formed from a single sheet of metal bent at the points 5, 6, 7, 8, 9, 10, 11, 12, 13, 14, and 15, which bends constitute a sash-rail having a closed seated groove to receive the panes of glass 16; but it will be understood that the groove for receiving the panes of glass can be varied as to width, owing to the fact that the side members of the sash-rail can be brought to or from each other, the angled portion 17 being formed of a width greater than the width of the groove, as illustrated in Figs. 3 and 4. By this arrangement a sash-rail can be manufactured with adjustable grooves for the panes of glass, thereby providing for various thicknesses of glass and at the same time leaving the groove in proper form and size to fit various thicknesses of glass.

In use the sash-rails should be held against springing after they have been properly adjusted to receive the proper thickness of glass by solder or otherwise, thereby preventing any springing after the panes of glass have been properly placed in position.

For the purpose of providing a means for placing the panes of glass in position one of the horizontal rails and one of the vertical rails should be provided with open grooves, as illustrated at 18, Fig. 5, by which arrangement the panes of glass can be extended into the space 19 and then moved in the opposite direction and properly seated in the groove opposite from the open one.

For the purpose of providing a means for tilting a sash-frame, as illustrated in Fig. 3, the pivot-pins 20 are provided, which may be of any form suitable for attachment to the casing and also attachment for the vertical sash-rails 1.

For the purpose of normally holding the upper sash-frame in a closed position the pivot-pins or posts should be located slightly above the horizontal center or the lower portion of the sash-frame should be weighted. However, this is a matter of mechanical construction only.

The horizontal sash-rails 1 of the upper sash and the upper of the lower sash-frame should be provided with a single flange 21,

- by which arrangement they can be brought into the position illustrated in Fig. 2. For the purpose of connecting the vertical and horizontal rails together at their angles on 5 either the vertical or horizontal rail, as the case may be, is provided with the groove 22, formed by bending the metal so that the flange 23 can be entered in the groove 22, by which arrangement the two sash-rails will 10 connect together; but in order to permanently hold the same in proper relative position rivets or solder should be provided, by which arrangement a strong rectangular frame is produced.
- 15 The stiles 24 and 25 are substantially of the form shown in Fig. 4, the stile 24 being provided with the web 26, which web provides a means for seating the screws 27 so as to properly connect the stiles together after the panes 20 of glass have been properly seated, by which arrangement the panes will be held in proper relation one with the other.
- The casing 28 is formed of metal and is formed so as to provide guides for the vertical movements of the sash-frame or for the pivoted frame to allow said pivoted frame to rock. The stop-flanges 29 are provided, and for the purpose of properly bracing said flanges the connecting member 30 is provided.
- 30 The casing 29 is so formed that the chambers or channels 31 and 32 will be formed to receive brick or timbers, as the case may be. It will be understood that the casing 28 should be formed of standard size, so that standard-size brick can be used. However, this is a matter of mechanical formation and does not enter into the detailed formation so far as the invention is concerned.
- For the purpose of holding the upper window-sash in the position illustrated in Fig. 3 40 the upper rail of the lower sash-frame is provided with the hooked bar 33, which hooked bar receives the lower end of the chain 34, which chain is attached to a suitable link 35, 45 connected to the upper rail of the upper sash.

I have defined the device for holding the sash-frame in a tilted position as a "chain," but it will be understood that any flexible device may be employed without departing from the nature of my invention.

The casing is so formed that the upper and lower window-sash frames will be in the same vertical plane when in their normal or closed positions, by which arrangement the lower sash cannot be moved upward or opened, owing to the fact that the upper sash-frame is in the same vertical plane. In use the upper pivoted sash-frame is turned upon its pivotal pins, after which the lower sash is free to be moved upward any desired distance, it of course being understood that the upward movement will be limited by reason of the upper sash-rail of the lower sash-frame coming in contact with the inclined under side of the upper sash-frame when said upper sash-frame is turned at an angle to a vertical line.

Having fully described my invention, what I claim as new, and desire to secure by Letters Patent, is—

1. A sash-rail for the purpose designed 70 formed of a single piece of metal and provided with a glass-receiving groove, said groove adapted to be adjusted to different widths, and a portion of the metal located across the groove and formed of a width 75 greater than the normal width of the groove, substantially as and for the purpose specified.
2. As an improved article of manufacture, a sash-rail formed of a single piece of metal and provided with an adjustable glass-receiving groove and means for closing the seat of the groove, substantially as and for the purpose specified.

In testimony that I claim the above I have hereunto subscribed my name in the presence 85 of two witnesses.

CHARLES W. ECKER.
